HANDLE-ACTUATED BLIND RIVETING TOOL

James Norman Henshaw, Leicester, England, assignor to United Shoe Machinery Corporation, Flemington, N. J., a corporation of New Jersey.

Application October 7, 1950, Serial No. 188,930
In Great Britain January 27, 1950

9 Claims. (Cl. 218—19)

1

This invention relates to fastener inserting tools and more especially to tools of a type adapted to install tubular rivets in a structure accessible from one side only. Although hereinafter illustrated as embodied in a tool for inserting and upsetting blind rivets of a particular construction, it will be apparent that use of the invention is not necessarily limited to the riveting tool as shown nor to the application of two-part fasteners of the type illustrated and about to be described.

An effective and rather well-known form of blind rivet comprises a tubular member of relatively ductile material having a head at one end and a mandrel extending longitudinally through the tubular portion. When this rivet is inserted in a hole in a structure to be riveted, a riveting tool grips and retracts the mandrel stem while holding the preformed head in abutting relation to the structure, and the relative endwise movement of the mandrel upsets the inaccessible end of the member. Continued pulling on the mandrel when the member sufficiently resists further endwise upsetting movement results in the breaking off of the expandable portion of the mandrel stem at a frangible constriction formed therein. Since with such rivets considerable force must be exerted by the tool first to move the upsetting mandrel relatively to the member and thereafter, if desired, to break the stem, a powerful tool which may be readily wielded by an operator is highly desirable. A manually operated tool for setting rivets of the type described is disclosed, for example, in United States Letters Patent No. 1,829,696, granted to H. N. Wylie et al.

An object of this invention, accordingly, is to provide an improved fastener inserting tool capable of installing blind rivets by exerting rivet setting stress, the power for which may be developed manually, stored temporarily in the tool, and thereafter conveniently applied as desired with but one hand.

With this object in view, a primary feature of the invention resides in the provision of a compact blind rivet inserting tool comprising mechanism for gripping and pulling one part of the rivet while a force of reaction is applied to another part, a compression spring for operating said mechanism, manual means for loading the spring, and means for releasing the potential energy of the spring to effect rivet upsetting.

The above and other features of the invention together with novel arrangements and combinations of parts will now be described in more de-

2

tail in connection with one illustrative embodiment and the accompanying drawings thereof, in which:

Fig. 1 is a side elevation of a tool in cocked condition and constructed in accordance with one form of the invention, body portions being shown in longitudinal section and a portion of the handle being broken away;

Fig. 2 is a section of a body portion of the tool shown in Fig. 1 and taken along the same plane but indicating parts in gripping engagement with a mandrel of a blind rivet;

Fig. 3 is a view of parts of the tool, in longitudinal section along a plane at right angles to that of Fig. 1, the parts being in the relative positions shown in Fig. 1;

Fig. 4 is a view similar to Fig. 3 but showing the parts in the relative positions shown in Fig. 2;

Fig. 5 is a view similar to Figs. 1 and 2 but showing the tool at a later stage of operation, the rivet having been set and the mandrel stem broken;

Fig. 6 is a side elevation showing the relative positions of parts at one stage during cocking of the tool; and

Fig. 7 is a section of a detail taken on the line VII—VII of Fig. 5 and showing the mounting of plungers.

The tool comprises a main body generally designated 10 and a hollow pistol-grip handle 12 pivotally related thereto as will be described. The body 10 includes a cylindrical casing 14 to one end of which a centrally bored anvil or nose piece 16 is fixed, and at the other end of which is an integral frame 18. Opposite side plates 20, only one of which is shown in Figs. 1, 5 and 6, are secured to the body by screws 22 and are bridged by a pin 24. The handle 12 is provided with a pair of upwardly extending spaced plates 26 respectively having an ear portion pivotally mounted on the pin 24. The body 10 and handle 12 normally are in the initial position shown in Figs. 1 and 5, and angle Z (Fig. 1) between them measures about 110°. In this position a face 28 (best seen in Fig. 6) on the handle abuts lower edges of the plates 20, and means hereinafter described are provided for releasably holding the tool in such condition.

Mandrel gripping mechanism of any satisfactory type adapted to engage, retract and break a mandrel stem M upon being actuated by tensile force may be installed within the case 14. One mechanism found highly effective in overcoming slippage on even a smooth-stemmed

mandril is disclosed, for example, in a copending application Serial No. 84,016, filed on March 29, 1949, in the name of S. L. Gookin. For the purpose of the present tool, mandril gripping mechanism somewhat similar to that employed in the above-cited Wylie et al. patent is used. A cylindrical sleeve 30 is movable axially within the casing 14. One end of the sleeve has an internal frusto-conical surface 32 and the other end is adjacent to an abutment shoulder 33 formed in the casing and is threaded to receive a plug 34. A pair of opposed collet jaws 36 are respectively affixed to leaf springs 38 and the latter are secured to a block 40, the arrangement being such that the springs 38 urge the jaws apart. One end of a compression spring 42 engages the plug 34 and the other end urges the block 40 to the left, as viewed in Figs. 1 and 5, and relative to the sleeve 30.

Movement of the jaws 36 under the action of the spring 42 is advantageously controlled by a latch 44 (Figs. 3 and 4) extending through slots 46 in the sleeve 30 and transversely of the casing 14. A narrow portion 48 of the latch is slideable in a slot 50 in the casing and a wider portion 52 is slideable in a slot 54 in the casing, the two portions being connected by a step surface 51. A leaf spring 56 confined between the casing and a pin 58 projecting from the latch 44 normally holds the latch in a position such that its ears 60 engage the casing 14 as shown in Fig. 3.

The actuating mechanism of the tool comprises a tubular member 62 largely housed by the handle 12 and containing a strong compression spring 64. The member 62 is provided in its bottom with a buffer 65 of leather or other suitable material. A rod 66 extending axially of the spring 64 has a head 68 (Fig. 1) engaging the lower end of that spring, the upper end being seated against an abutment 70 formed in the handle. The rod 66 extends through a bore in the handle and has its upper end forked to receive a pin 72 for pivotally connecting with one end of a link 74. The link 74 extends into a groove in a cylindrical rotor 76 which is rotatably mounted on the pin 24. The other end of the link 74 is pivotally connected to a pin 78 fixed in the rotor 76 and bridging the groove to extend from both sides of the rotor. Also bridging the groove in the rotor and fixed to the latter is a pin 80. A link 82 has pivotal connections with the pin 80 and an extension 84 of the plug 34.

Adjoining ends of lapped toggle links 86 and 88 are pivotally connected by a pin 90. The other end of the link 86 has pivotal connection with a projecting portion of the pin 78, and the lower end of the link 88 has pivotal connection with a pin 92 secured to the plates 26. Another pair of toggle links (not shown) are counterparts and preferably duplicates of the pair of toggle links 86, 88, being similarly mounted on the opposite side of the rotor 76 and having like connection with the pins 78 and 92.

A trigger 94 is affixed to upwardly extending, flat sector-shaped members 96 (only one shown except in Fig. 7) pivotally supported on the pin 24 at opposite sides of the rotor 76. Each member 96 is disposed between the rotor and a plate 26, and is provided with an arcuate slot 98, the slots 98 being in register. A tubular pin 100 extends through the slots 98 and into the plates 26 thereby limiting pivotal movement of the toggle 94 about the pin 24. Round-ended, spring-pressed plungers 102 mounted in opposite ends of the pin 100 protrude into recesses in the plates

10 for the purpose of releasably holding the handle 12 relatively to the body 10 in the angular position shown in Fig. 1. For reasons to be explained it should also be noted that each member 96 is so arranged that when the trigger 94 is depressed, i. e., moved toward the handle 12, an upper portion of the toggle link 86 and its counterpart will be engaged and displaced from a locked or straightened toggle condition by a portion of one of the trigger members 96.

In operating the tool, a mandril M is thrust into the anvil 16 until the latter is engaged externally by the preformed head of a tubular portion R of the rivet. The mandril stem should then extend between the jaws 36 as shown in Figs. 1 and 2. In Fig. 1 the tool is shown when cocked. The spring 64, being compressed between the head 68 and the abutment 70, acts through the rod 66 tending to turn the rotor 76 clockwise as viewed in Fig. 1. Such turning is prevented, however, by the toggle 86, 88 which is then straight and serves as a strut. The sleeve 30 is then in its forward position, the jaws 36 are fully separated by the spring 38 to admit the mandril M, and the spring 42 holds the block 40 in engagement with the wider portion 52 of the latch 44 as shown in Figs. 1 and 3. By depressing the latch as shown in Fig. 4 the spring 42 is permitted to move the jaws toward the mandril end of the tool and they are closed on the mandril by reason of their engaging the surfaces 32. Though the latch 44 then be manually released, it will be held depressed by engagement of its surface 51 with the block 40. Conveniently, with one hand the loaded tool may be wielded by the handle 12 as desired and the rivet will be retained in the tool.

When the rivet R is inserted in the hole to be riveted, its preformed head being held against the structure by the anvil 16, the trigger 94 may be depressed. The toggle 86, 88 and its toggle counterparts are engaged by the trigger members 96 being thereby broken as aforesaid and the energized spring 64 being permitted to expand to actuate the mandril gripping mechanism. The force of the expansion moves the rod 66 downward until the head 68 engages the buffer 65. As a consequence, the rotor 76 is turned clockwise as viewed in Fig. 1 thereby acting via the link 82, extension 84, plug 34 and sleeve 30 to retract the jaws 36 with the mandril M relative to the anvil 16. Rivet upsetting so effected on the inaccessible side of the structure is followed by tensioning and breaking of the mandril M at its constriction, the broken portion remaining between the jaws 36 and the tool then being in the condition shown in Fig. 5.

During expansion of the spring 64 the block 40 is shifted sufficiently to disengage it from the surface 51 and the latch 44 returns to its normal position as shown in Fig. 3.

To energize the tool prior to inserting the next rivet therein, the body 10 is grasped with one hand and the handle 12 held with the other, these tool portions then being swung toward one another to pivot them about the pin 24 and lessen the angle Z. During the initial part of this pivotal movement an end of the sleeve 30 engages the shoulder 33 preventing further rotation (clockwise as viewed in Figs. 1 or 6) of the rotor 76 and downward movement of the rod 66. Further pivotal movement accordingly compresses the spring 64 between the head 68 and the abutment 70 and progressively straightens the toggle 86, 88. The tool is then in the condition illustrated in Fig. 6. The body 10 and

handle 12 may now be returned to their initial positions but the straightened toggle 86, 88 and its counterpart prevent the compressed spring 64 from expanding while the rod 66 and link 74 move upward to turn the rotor counterclockwise. The sleeve 30 and block 40 are thereby moved within the casing 14 toward the anvil 16. Before the sleeve has reached its most forward position the block 40 engages the latch 44 and comes to rest, continued movement of the sleeve thereafter permitting the jaws 36 to separate and release the broken mandril stem. In practice a rapid return stroke is found to expel the broken mandril stem and the tool is ready to install the next rivet.

Having thus described my invention, what I claim as new and desire to secure by Letters Patent of the United States is:

1. A tool for installing a two-part rivet comprising a body having an anvil for bracing one part of the rivet, gripping mechanism movable relatively to the body for retracting the second part of the rivet from the anvil, an element connected to said mechanism and movably mounted on the body, a spring, means for shifting said element with respect to the body and against compression of the spring, means for locking the element in shifted position to hold the spring compressed, and a trigger for releasing the element whereby said gripping mechanism is actuated by the energized spring.

2. A tool for installing a two-part rivet comprising a body having an anvil for bracing one part of the rivet, gripping mechanism movable relatively to the body for retracting the second part of the rivet from the anvil, a rotatable element mounted on the body and having operative connection with said mechanism, a handle pivotally related to the body, means energizable by pivotal movement of said handle for rotating said element, locking means for maintaining said means energized, and a trigger for releasing said locking means whereby the energized means is effective to actuate said gripping mechanism by rotating said element.

3. In a riveting tool provided with a body having an anvil for bracing one part of a rivet and mechanism for gripping and retracting a second part of the rivet relative to the anvil, a hollow handle pivotally related to the body, an element connected to said mechanism and movably mounted on the body, energizable means disposed in the handle for actuating said element and connected thereto, connections between the handle and the element for energizing said means by movement of the handle in one direction, the connections being adapted to lock said means in energized condition on return movement of the handle, and a trigger adjacent to the handle and movable to unlock the energized means by engagement with said connections whereby said element is actuated to move said mechanism relatively to the body.

4. A riveting tool comprising a body having an anvil for bracing one part of a rivet, mechanism in the body for gripping and retracting a second part of the rivet relative to the anvil, a hollow handle pivotally related to the body for movement lengthwise thereof, a rotatable element supported by the body and operatively connected to said mechanism, means in the handle and operable thereby for rotating said element to actuate said mechanism, said means including a rod having pivotal connection with the element, a toggle connecting the element and handle, and

a resilient member compressible by the rod after straightening of the toggle by movement of the handle, and a trigger associated with the handle and arranged to be depressed to engage and break said toggle whereby the compressed member is enabled to act on said element by means of said rod.

5. In a riveting tool of the type having a body provided with mandril gripping mechanism, a pivot pin affixed to the body, a handle supported by the pin, means energized by movement of the handle relative to the body for moving the gripping mechanism axially thereof, said means including a rotor rotatably mounted on the pivot pin and having eccentric connection with said mechanism, a spring-backed rod disposed in the handle and having eccentric pivotal connection with the rotor, a toggle connecting the rotor eccentrically with said handle and straightenable to lock the rotor against rotation during energizing movement of the handle, and a trigger depressible relatively to the latter for breaking the toggle to release said rotor.

6. In a riveting tool having a body, an anvil, and mechanism in the body for gripping and retracting part of a rivet relative to the anvil, a rotor pivotally mounted in the body and connected to the mechanism, a handle movable with respect to the body, said handle housing a rod connected to the rotor and a spring acting on said rod, the arrangement being such as to increase the actuating influence of said spring on the rod by movement of the handle in one direction, means for maintaining the increased actuating influence during reverse movement of the handle, and a trigger engageable with said means to enable the spring to turn said rotor.

7. A blind riveting tool comprising a body and a pivotally related handle, the body having an anvil adapted to brace a part of a rivet, mechanism enclosed by the body for gripping and retracting another part of the rivet relative to the anvil, a rotor fulcrumed on the body and having a pivotal connection with said mechanism, a pivot on the rotor, means extending within the handle and connected to the pivot for moving the rotor, said means including a rod and a spring acting thereon, a toggle connected to the pivot and straightenable by movement of the handle toward the body, said spring being disposed to be energized by such handle movement, and trigger means for breaking said toggle to release the energy of said spring.

8. A riveting tool comprising a body, a sleeve movable axially therein and provided with an end having an internal conical surface, rivet gripping mechanism secured to the interior of the sleeve and yieldable axially thereof, said mechanism including a spring pressed member and a pair of leaf springs secured to the member for individually supporting a pair of rivet gripping jaws in spread-apart condition, and a stepped latch extending transversely of the body and yieldingly movable therein for engagement with said member, one portion of said latch normally serving to prevent the member from urging said jaws into cooperative relation with said surface and another portion of said latch being effective on displacement thereof to enable the member to move said jaws into cooperative relation with said surface.

9. A riveting tool comprising a main body having an anvil end, a sleeve movable in the body having an end provided with an internal conical surface, a yieldable member secured in the

sleeve adjacent to its other end, leaf springs secured to the member and disposed to support rivet gripping jaws in spread-apart condition adjacent to said surface, mechanism for moving the sleeve toward and from the anvil end, and means for releasably limiting the movement of the jaws toward said surface, said mechanism including a rotor pivotally mounted in the body and connected to the sleeve, a pistol-grip handle pivotally related to the body, a rod in the 10

handle pivotally connected to the rotor, a spring arranged to act on the rotor by means of said rod, said spring being energizable by movement of the handle relative to the body, a trigger, and locking means for constraining the mechanism against relative movement of the sleeve until released by the trigger.

JAMES NORMAN HENSHAW.
